ADJUSTABLE CAR SEAT AND INDICATOR.

No. 400,241.

Patented Mar. 26, 1889.

UNITED STATES PATENT OFFICE.

ONESIME E. MICHAUD, OF ST. LOUIS, MISSOURI.

ADJUSTABLE CAR-SEAT AND INDICATOR.

SPECIFICATION forming part of Letters Patent No. 400,241, dated March 26, 1889.

Application filed Marc' 2, 1888. Serial No. 265,960. (No model.)

To all whom it may concern:

Be it known that I, ONESIME E. MICHAUD, of St. Louis, Missouri, have made a new and useful Improvement in Adjustable Car-Seats and Indicators, of which the following is a full, clear, and exact description.

I have heretofore made an improvement, patented August 14, 1888, No. 387,898, in registers of the kind under consideration, and in which the mileages of the passengers are registered in an aggregate form, and the operation of the register mechanism effected by means of and according to the character of the adjustment of the car-seat. In the construction referred to the car-seat is adaptable either to a non-paying passenger, to a half-rate passenger, or to a full-rate passenger, and these various adjustments are accomplished by means of arms capable of being turned upward into the plane of the chair-back or downward over the chair-seat, and which, when turned downward, serve, as the case may be, either to narrow the seat for a half-rate passenger or to divide it for non-paying passengers.

The present improvement relates to the car-seats and to the means for narrowing and dividing the seat, and for transmitting the movement of the parts used in the seat-adjustment to the register mechanism.

In the annexed drawings, making part of this specification, and illustrating the most desirable mode of carrying out the improvement, Figure 1 is a view showing the car-seat in front elevation and the adjacent side of the car in vertical cross-section. Fig. 2 is a plan of the seat-frame, the arms being adjusted as for non-paying passengers; Fig. 3, a similar view of the seat-frame, the arms being adjusted as for half-rate passengers; Fig. 4, a third view of the seat-frame, the arms being adjusted as for full-rate passengers; Fig. 5, a side elevation of the seat. The view also illustrates the indicator. Fig. 6 is a view in perspective of one of the movable arms of the seat; Figs. 7, 8, and 9, details, being vertical sections of that part of the movable arm and seat-frame used in locking the movable arm at the desired point of adjustment. The key is shown in position in Figs. 8 and 9. Fig. 10 is a view in perspective of the key; Fig. 11, a

horizontal section of that portion of the car-side with which the seat-cord pulleys are immediately connected, and Fig. 12 a front elevation of the indicator-target.

55

The same letters of reference indicate like parts.

A represents an ordinary car-seat, saving as it is modified by the embodiment therein of the improvement in question. It is divided 60 into two compartments, a and a', by means of the fixed arm B. Each of the compartments a a' can be adapted to receive a full-rate passenger, a half-rate, or a non-paying one in the following manner:

65 C represents an arm adapted to be slipped in the direction of the width—that is, in the direction of the double-headed arrow x, Fig. 1—from a position immediately alongside the arm B (indicated in broken lines, Fig. 1, and shown in full lines, Fig. 4) into a position midway in the width of the compartment a, as shown in Figs. 1 and 2, in which position the compartment a is adapted to receive a non-paying passenger. The position of the arm D, 70 Fig. 1, (it being nearer to one side of the compartment a') adapts that compartment (a') to a half-rate passenger. When the arms C D are respectively alongside the arms B E, as indicated by the broken lines, Fig. 1, the compartments a and a' can each receive a full-rate passenger. The arms C D are adapted to be moved by hand in the manner described, and they are adapted to be locked in any position by some suitable means, such as the 85 spring-dog F, which is attached to the base c of the arm and made to press downward into the perforation f. To release the arm, a key, G, is inserted in the key-hole g until it comes beneath the spring-arm f' of the dog, and then 90 by rotating the key, as indicated in Fig. 9, the dog is raised out of the perforation f and the arm C or D is free to be shifted. The movement of each of the arms C D is communicated to a mileage-registering mechanism, 95 (not shown,) as follows:

H represents a rod jointed at one end to the lug c' upon the arm-frame and at the other end to a lever, I, which at i is pivoted to enable it to be turned, as indicated by the broken 100 lines, Fig. 1, as the arm C is shifted. A cord, J, leads from the lever I around the pulley j

to the indicator K, and as the lever I is turned either to a half-way or to a full-way position the target L of the indicator is adjusted accordingly—that is, when the seat-arm C is 5 midway in a compartment, a , the blank space l of the target appears. When the seat-arm is adjusted for a half-rate passenger, the half-rate sign l^1 appears, and when the seat-arm is adjusted for a full-rate passenger the full-rate sign l^2 , Fig. 12, is brought into view at the opening l^3 , Fig. 5. A similar rod, H', connects the other arm, D, with a similar lever, I', whose cord J' is similarly connected with a similarly-operating target, L'.

15 The levers I I' are also each provided with a cord, M and M', respectively, which leads around a pulley, m and m', respectively, to the mileage-register, and which cords M M', respectively, and according to the positions 20 of the seat-arms C D, serve to control the operation of the mileage-register—that is, the arms C D, when adjusted alongside the arms B E, respectively cause the levers I I' and the cords M M' to be moved a certain distance, and the mileage-register thereby adjusted to effect full-fare registration; and when the arms C D are shifted to form a half-fare seat the cords M M' are not moved as far, and the mileage-register is thereby adjusted to 25 effect half-fare registration. As the mileage-register is constructed and operated as in the improvement referred to, it is unnecessary here to explain its nature in detail. The cords M M' act just as does the connection which 30 leads from the car-seat to the mileage-register in the original construction.

The arm-base c is adapted to slide in the car-seat frame a^2 beneath the surface a^3 of the

car-seat, and to that end the frame a^3 is suitably slotted at a^4 and otherwise shaped at a^5 , 40 substantially as shown, to permit of the frame being moved toward and from the car-seat ends. The perforation f is in the car-seat frame.

I desire not to be restricted to the particular means shown for communicating the arm motion to the indicator and mileage-register, it being obvious that other devices can therefore be substituted. I prefer, however, the device shown. The arm-base of the arm C is 50 shaped, as shown at c^2 , to provide room for the rod H' of the arm D.

I claim—

1. The combination of the car-seat, the movable arm C, the rod H, lever I, cord J, indicator-target, the car, and the cord-bearings, 55 substantially as described.

2. The combination of the car, the car-seat having the compartments a a' , the arms C D, the rods H H', the levers I I', the cords J J', 60 and the indicator and target, substantially as described.

3. The combination, with a seat having a laterally-adjustable arm, of an indicator and actuating devices arranged to be operated by 65 said arm for different indications according to the adjustment of the latter, substantially as set forth.

4. The combination of the car-seat, the laterally-adjustable arm, the dog, and the key, 70 substantially as described.

Witness my hand.

ONESIME E. MICHAUD.
